by E. E. Masson, Attorney.

UNITED STATES PATENT OFFICE.

JONAS L. KNOLL, OF LEBANON, PENNSYLVANIA.

DESIGN FOR A BICYCLE-FRAME.

SPECIFICATION forming part of Design No. 31,448, dated August 22, 1899.

Application filed July 31, 1899. Serial No. 725,698. Term of patent 14 years.

To all whom it may concern:

Be it known that I, JONAS L. KNOLL, a citizen of the United States, residing at Lebanon, in the county of Lebanon and State of Pennsylvania, have invented and produced a new and original Design for a Bicycle-Frame; and I do hereby declare the following to be a full, clear, and exact description of the same, reference being had to the accompanying drawing, forming a part thereof.

The drawing represents my bicycle-frame in perspective.

As shown in the drawing, the leading feature of my design consists in the backbone A, 15 representing a flat spring-bar slightly arched and having its rear end bent more acutely and forked into two branches *a a*, the seat-post B representing a flat spring-bar having its lower end attached to the shaft-hanger C 20 and its upper end to the bottom of the backbone, the front reach D representing a straight flat spring-bar uniting the shaft-hanger C to the front sleeve of the steering-rod. A flat bar E has one end secured to the front reach

and the other end to the bottom of the backbone, its middle portion being bent rearwardly and secured to the seat-post at *e*. A straight spring-brace F has one end secured to the rear of the seat-post adjacent to the middle portion *e* and its rear end to the acutely-bent 30 portion of the backbone. The frame has also a flat-bar brace G, uniting the front half of the backbone to the bottom of the sleeve of the steering-rod, and a small brace-bar *g* also unites the brace G to the bottom of the backbone.

Having described my invention, what I claim, and desire to secure by Letters Patent, is—

The design for a bicycle-frame as herein 40 shown and described.

In testimony whereof I affix my signature in presence of two witnesses.

JONAS L. KNOLL.
